UNITED STATES PATENT OFFICE.

RAPHAEL A. PORTER, OF PAYSON, UTAH.

VEGETABLE SLICER.

Application filed November 15, 1922. Serial No. 601,105.

To all whom it may concern:

Be it known that I, RAPHAEL A. PORTER, a citizen of the United States, residing at Payson, in the county of Utah and State of Utah, have invented certain new and useful Improvements in Vegetable Slicers, of which the following is a specification, reference being had to the accompanying drawings.

This invention relates to devices for preparing vegetables, and particularly to means for slicing or dicing vegetables such as potatoes or other commodities which it may be desired to cut up into pieces of uniform size.

15 One of the objects is to provide a device of this kind having knives extending in two series transversely of each other, with means whereby the knives of either set may be readily removed and re-adjusted so as to increase or decrease the size of the slices, cubes or other pieces cut by the knives.

A further object is to provide improved means whereby the knives may be tensioned, said means also acting to lock the knives in place.

25 A still further object is to provide a mechanism of this character wherein the knives are firmly held in place under ordinary circumstances, but in which any one 30 knife may be readily removed if at any time it is desired to replace this knife or to take the knives out for sharpening.

Another object is to provide a device of this character which may be so adjusted as 35 to slice the vegetable into very thin slices, into larger slices, or whereby the vegetable can be cut into small square pieces.

Other objects will appear in the course of the following description.

40 My invention is illustrated in the accompanying drawings, wherein:—

Figure 1 is a plan view of a vegetable slicer constructed in accordance with my invention, the frame being broken away;

45 Figure 2 is a side elevation thereof;

Figure 3 is a section on the line 3—3 of Figure 1.

Referring to these drawings, it will be seen that one of the elements of my improved cutter is a frame which is rectangular in plan view and consists of four side pieces 10 and 10^a having miter joints 11. These side pieces 10 and 10^a are not connected to each other at the miter joints but simply engage against each other. Thus these pieces 10 and 10^a are able to shift with

relation to each other within certain limits. Each of these members 10 and 10^a, as illustrated in Figure 3, has a vertical outer face, a vertical inner face 12 extending downward for a certain distance from the top face 13, and a downwardly and outwardly inclined face 14. Transverse slots 15 extend upward from the lower edge of each member 10 to any desired distance. The outer face of each member 10 or 10^a is formed with a longitudinally extending groove 16 which intersects the slots or kerfs 15.

Coacting with the opposite members 10 are a series of blades 17 of a length sufficient to extend across the frame formed by the members 10 and 10^a and to project slightly beyond the outer faces of these members. These blades are apertured at the ends for a rod 18 which fits within the recess 16 and extends through the like ends of all of that series of blades. The members 10^a have the kerfs or slots 15 extended to a greater depth than the kerfs of the members 10, and the grooves 16 are disposed on a level lower than the grooves 16 in the members 10^a. As a consequence of this, the series of blades 17 are disposed on a lower level than the blades 17^a. These blades 17^a are held in place in the members 10^a in exactly the same manner as the blades 17 are held in place in the members 10. The upper edges of the blades 17 may be slightly toothed or may be beveled, but I do not wish to be limited to the exact formation of these cutting edges.

Coacting with the frame formed by the members 10 and 10^a is a rectangular base frame 19 formed of side and end pieces but these side and end pieces are rigidly engaged with each other. This frame, as illustrated most clearly in Figure 3, has a vertical inner face 20, a face 21 which extends upward from the lower face of the frame a certain distance, and a face 22 which is upwardly and inwardly inclined so as to have wedging engagement with the faces 14 of the members 10 and 10^a. The frame 19 is likewise formed with slots 23 corresponding to the slots 15 and adapted to fit over the blades 17 and 17^a. When the first named frame is forced downward, it will be obvious that it will have wedging engagement with the base frame 19 and that it will tend to force the members 10 away from each other and the members 10^a away from each other. In other words, the frame will be expanded equally in all directions. This

expansion of the frame will tension the knives 19.

The frame 19 constitutes an expander and any suitable means may be provided for forcing this upper frame downward onto the expander to expand the frame 19. I have illustrated for this purpose, however, transverse braces 24 and 25, the brace 24 being disposed below the lower frame 19 and the brace 25 above the upper frame, and passing through these braces at the corners of the two frames are the bolts 26 having the nuts 27. By tightening up upon these nuts it will be seen that the frame 19 may be forced into the frame formed of the members 10 and 10^a and thus the cutters or blades be expanded in all directions, thus securing a very high degree of tension on these blades so that the blades will not bend in actual use. Under some circumstances it is, of course, advisable that the vegetables to be cut or diced shall be forced mechanically through my device and past the blades 17 and 17^a. I do not wish to be limited to any particular means for this purpose, as many machines of the same general character as mine are provided with means of this kind and such means is well known. A plunger may be used, for instance, operating within the frame 19 to force the vegetables through the knives. This plunger may be operated by a screw, lever, or by a crank shaft. I have illustrated a simple means for this purpose wherein the plunger 28 is operated by means of a lever 29, but any other means might be used without departing from the spirit of the invention as defined in the appended claims.

These machines may be made of any size from a very small size for kitchen use to a large size for commercial use, and are of particular value for the preparation of potatoes and potato products, though obviously the machine might be used for other purposes. It will be seen that by entirely removing one series of knives and using all of the knives of the other series that a vegetable may be sliced into very thin slices, and that by filling all of the slots in both series of slots with knives the vegetables can be cut into very small square pieces, and that by removing more or less of the knives from either one series or the other series or both series that the vegetables may be cut into any desired size or rectangular form.

Of course, I do not wish to be limited to the exact details of construction illustrated, as these may be varied in many ways, but a device of this character is very simple, convenient and effective and is particularly valuable in preparing potato products for the market.

I claim:—

1. A vegetable cutter including coacting rectangular frames, one of said frames be-

ing formed of separate sections, the sections being shiftable away from each other, the confronting faces of the frames being beveled downward and inward whereby when said frames are forced toward each other the sections of the first named frame will be forced uniformly away from each other, and a series of blades carried by the first named frame, the separation of said sections under the action of the second named frame acting to tension said blades.

2. A vegetable cutter including coacting rectangular frames, one of said frames being formed of separate sections, the sections being shiftable away from each other, the confronting faces of the frames being beveled downward and inward whereby when said frames are forced toward each other the sections of the first named frame will be forced uniformly away from each other, both of said frames being formed with kerfs extending inward from their confronting edges, and a series of knives disposed in the kerfs of one frame an having their outer ends engaged with the outer faces of the sections of the first named frame.

3. A vegetable cutter including coacting rectangular frames, one of said frames being formed of separate sections, the sections being shiftable away from each other, the confronting faces of the frames being beveled downward and inward whereby when said frames are forced toward each other the sections of the first named frame will be forced uniformly away from each other, both of said frames being formed with kerfs extending inward from their confronting edges, and a series of blades disposed in the kerfs of the first named frame, the blades being apertured at their outer ends and projecting beyond the outer face of said first named frame, and rods extending through said apertures and bearing against the faces of the sections of said first named frame.

4. A vegetable cutter including coacting rectangular frames, one of said frames being formed of separate sections, the sections being shiftable away from each other, the confronting faces of the frames being beveled downward and inward whereby when said frames are forced toward each other these sections of the first named frame will be forced uniformly away from each other, both of said frames being formed with kerfs extending inward from their confronting edges, a series of blades disposed in the kerfs of the first named frame, the blades being apertured at their outer ends and projecting beyond the outer face of said first named frame, and rods extending through said apertures and bearing against the faces of the sections of said first named frame, the outer faces of said sections being grooved to receive said rods.

5. A vegetable cutter including coacting

- rectangular frames, one of said frames being formed of separate sections, the sections being shiftable away from each other, the confronting faces of the frames being beveled downward and inward whereby when said frames are forced toward each other the sections of the first named frame will be forced uniformly away from each other, both of said frames being formed with kerfs of opposed sections of the first named frame, a series of blades at right angles to the first named blades and disposed in the kerfs of the other sections, means engaging the ends of the blades against the outer faces of said sections, and means for forcing the expander toward the sectional frame to thereby spread the sections of said frame. 50
- 5 10 extending inward from their confronting edges, a series of blades disposed in the kerfs of the first named frame, the blades being apertured at their outer ends and projecting beyond the outer face of said first, 60
- 15 named frame, rods extending through said apertures and bearing against the faces of the sections of said first named frame, and means for forcing said frames together to cause the second named frame to wedge the 65
- 20 sections of the first named frame outward. 70
6. A vegetable cutter including coacting frames, one of said frames being formed of separate sections shiftable away from each other, means acting when said frames 75
- 25 are forced toward each other to cause the sections of the first named frame to be forced away from each other, and a series of blades carried by the first named frame, the separation of said sections acting to tension the blades. 80
- 30
7. In a vegetable cutter and slicer, a frame composed of four sections in rectangular relation and the sections having miter joints and abutting against each other 85
- 35 at their ends but being separate from each other, rectangular expander coacting with the first named frame, the abutting faces of the expander and of the sections of the frame having upwardly and outwardly inclined faces whereby when the expander is 90
- 40 inserted into the first named frame it will cause the expansion of the sections of the latter, opposite sections of the first named frame having a series of kerfs extending 95
- 45 from the edge of the section, the confronting portion of the expander having a like series of kerfs, a series of blades extending in one direction and passing through the
- kerfs of the other sections, means engaging the ends of the blades against the outer faces of said sections, means for forcing the expander toward the sectional frame to thereby spread the sections of said frame, and means for forcing the vegetables to be cut against said blades. 85
8. In a vegetable cutter and slicer, a frame composed of four sections in rectangular relation and the sections having miter joints and abutting against each other at their ends but being separate from each other, a rectangular expander coacting with the first named frame, the abutting faces of the expander and of the sections of the frame having upwardly and outwardly inclined faces whereby when the expander is inserted into the first named frame it will cause the expansion of the sections of the latter, opposite sections of the first named frame having a series of kerfs extending from the edge of the section, the confronting portion of the expander having a like series of kerfs, a series of blades extending in one direction and passing through the 75
9. In a vegetable slicer and cutter, an expandible frame supporting a series of cutters, an expander which when forced against said frame causes the expansion thereof, cutters carried by the first named frame, and means for forcing the frame and expander toward each other to thereby expand the first named frame. 90

In testimony whereof I hereunto affix my signature.

RAPHAEL A. PORTER.
